DESIGN FOR A RADIO RECEIVING SET

David Housman, Boston, Mass.

Application March 13, 1939, Serial No. 83,543

Term of patent 3½ years

To all whom it may concern:

Be it known that I, David Housman, a citizen of the United States, residing at Boston, in the county of Suffolk and State of Massachusetts, have invented a new, original, and ornamental Design for Radio Receiving Sets, of which the following is a specification, reference being had to the accompanying drawing, forming part thereof.

The figure is a perspective view of a radio receiving set, showing my new design, the left hand end portion of my radio receiving set being identical in design with the right hand end portion.

I claim:

The ornamental design for a radio receiving set, as shown and described.

DAVID HOUSMAN.
